SIGNALING SYSTEM

Ralph R. Kemmerer, Swissvale, Pa., assignor to
The Union Switch & Signal Company, Swiss-
vale, Pa., a corporation of Pennsylvania

Application April 5, 1935, Serial No. 14,865

20 Claims. (Cl. 246--77)

My invention relates to signaling systems, and particularly to signaling systems for governing the passage of vehicles along a trackway such as, for example, railway trains.

5 A feature of my invention is the provision of apparatus for a non-contact intermittent control signaling system which is particularly adaptable for use, although in no manner limited thereto, on non-track circuited railways and on railways 10 using vehicles which may not effectively operate track circuits. A further feature of my invention is the provision of apparatus for signaling systems of the intermittent control type where- 15 with a vehicle or a train of several vehicles is registered into a block of a definite length of the trackway and is again registered as it passes out of such block, and which apparatus is effective to determine the passage of the entire train into the block and to set a signaling device in the position 20 to protect the train before the signaling device of a similar block in the rear of the block occupied is permitted to assume a proceed indication. Still another feature of my invention is the provision of apparatus for intermittent con- 25 trol signaling systems wherewith two different forms of actuators cooperate to differentiate between the front and rear ends of trains. Again, a feature of my invention is the provision of apparatus of the type here involved which is effec- 30 tive to protect movements in and out of a block of the trackway at points other than at the entrance and exit of such block, such as, for example, a siding of a railway track. Other features and 35 advantages of my invention will appear as the specification progresses.

I will describe one form of apparatus embodying my invention, and will then point out the novel features thereof in claims.

40 For a better understanding of my invention reference may be had to the accompanying drawings in which Figs. 1a and 1b when taken together with Fig. 1a placed at the left are a diagrammatic view of one form of trackway apparatus embodying my invention when applied to a railway. Fig. 45 2 is a diagrammatic view of one form of train-carried apparatus which may be employed for cooperating with the apparatus of Figs. 1a and 1b.

In each of the several views like reference characters designate similar parts.

50 Although my invention is here disclosed as applied to a railway it is to be understood that I do not limit myself to this one particular application of the invention and other embodiments will suggest themselves to those skilled in the art. 55 This one application of the invention will serve,

however, as an illustration of the many places the invention will be useful.

By referring to Figs. 1a and 1b, I will first describe the trackway apparatus, and then follow that by a description of the train-carried apparatus of Fig. 2. The reference characters 11 and 11^a designate the traffic rails of a railway along which traffic normally moves in the direction indicated by an arrow and which direction for convenience I will term east or eastbound. 10 The trackway is arranged into blocks of any convenient length by locating wayside signal equipment at each of a plurality of spaced intervals along the trackway. In Figs. 1a and 1b two such signal locations designated by the reference characters 1 and 3 are shown. It follows that the stretch of trackway between the locations 1 and 3 forms one block and which is designated as a whole by the reference character Y, the location 1 being the entrance of the block Y and the location 15 3 being the exit of that block. The block to the left of block Y is designated as a whole by the reference character X, and the block to the right of the block Y is designated by the reference character Z. Hence, the location 1 which is the 20 entrance of block Y is the exit of the block X, the entrance of block X not being shown. The location 3 which is the exit of block Y is the entrance of block Z, the exit of block Z not being shown. In the block Z a track switch 3W leading to a siding track W is located. While in the drawings only one full block, the exit end of a second block and the entrance end of a third block are disclosed, it will be understood that the full length 25 of the railway is arranged in consecutive blocks 30 35 similar to the blocks X, Y, and Z.

At each signal location, two vehicle controlled actuators for registering a vehicle or train into the block for which that location is the entrance and for subsequently registering the train out 40 of the block for which that location is the exit are provided. A first one of these actuators I will for convenience refer to as a receiving unit and the second actuator I will refer to as a detecting unit. These actuators may take different 45 forms and as here shown the receiving unit is an electromagnetic device and the detecting element is a photo-electric device. Each receiving unit includes a wayside receiver, a rectifier and a receiving relay; and each detecting unit includes a light unit, a light responsive unit and a detecting relay.

Referring specifically to location 1 at the junction of blocks X and Y, the wayside receiver 1R of the receiving unit has its winding 12 connected 55

with the input terminals of a full wave rectifier IRX , the output terminals of which are connected by wires 13 and 14 with the control winding of a receiving relay IZR . This wayside receiver IR may take different forms several of which are well-known and it is deemed sufficient for this application to point out that this receiver is preferably made up of a laminated iron magnetic core in U form, around which the winding 12 is placed. This receiver is completely enclosed in a non-magnetic casing for mechanical protection and the entire device is secured to the track ties, the core of the receiver being parallel to the traffic rails outside of the rails and in a position for magnetic relationship with a train-carried inductor to be referred to later. As will appear hereinafter, the train-carried inductor when passing over the wayside receiver IR is effective to induce an electromotive force in its winding 12 . This induced electromotive force when rectified by the rectifier IRX energizes the relay IZR , which when momentarily picked up is retained in its energized position by virtue of a stick circuit traced from the B terminal of any convenient source of current such as a battery not shown, over back contact 15 of a relay IXR to be shortly described, wire 16 , front contact 17 of a relay IZR , wires 18 and 14 , winding of the relay and wires 13 and 19 to the opposite terminal C of the same source of current. The parts are so arranged that the polarity of the current supplied to the winding of the relay IZR over this stick circuit is the same as that of the energizing current supplied through the rectifier, and hence relay IZR once picked up in response to the electromotive force induced in the receiver winding 12 is retained energized over the stick circuit as long as the back contact 15 of the relay IXR remains closed.

Still referring to location 1 , a light unit IL of the detecting unit is located on the left-hand side of the track and is arranged to direct a light beam across the track rails as indicated by dotted lines to a light sensitive unit ILC on the right-hand side of the track. The light unit IL may take different forms and preferably is an electrically lighted lamp constantly supplied with current from any convenient source over the two lead wires 20 and 21 , the lamp for the unit IL being enclosed in a suitable weatherproof housing. Preferably the light beam from the unit IL crosses the traffic rails at a distance sufficiently high above the top of the rails so as to pass over the heads of individuals walking along the track but so as to be intercepted by a railway car. Furthermore, the light unit IL is preferably set to direct its light beams diagonally across the traffic rails as indicated by the dotted lines, the diagonal arrangement being effective to assure continuous interception of the light beam as long as a car or a train of several cars is passing. If the light beam was directed at right angles across the traffic rails, it might flash between the cars of a train. The light sensitive unit ILC may be of the photo-conductive, photo-voltaic, or photo-emissive type, as desired, and is shown conventionally only since its specific structure forms no part of my invention. As here shown, the light sensitive unit ILC is associated with an amplifier IX the output of which includes the control winding of the detecting relay IXR . The arrangement is such that as long as the unit ILC is exposed to the light beam from the unit IL sufficient current is supplied to the relay IXR to effectively energize that relay,

but that when the light beam is intercepted the current supplied to the relay IXR is so reduced the relay is released. It is to be pointed out that while I have referred to the unit IL as a source of light such as an electric lamp and the unit ILC as a light sensitive unit responsive thereto, it will be understood that I do not wish to limit myself to this one arrangement and the unit IL may be a source of so-called quasi-optical rays and the respective unit ILC may be a suitable receiver responsive to such rays. The particular value of this latter arrangement is that while it in general performs its function in similar manner to the light sensitive cell, it is immune to the influence of the source of light rays not directly associated with the operation of the system and hence the device is sensitive only to a certain optical characteristic. It is clear that when the head end of a vehicle or train intercepts the light beam the relay IXR is released and subsequently remains down in engagement with its back contacts until the rear end of the train passes beyond the location and the light sensitive unit ILC is again exposed to the light beam. In Fig. 1a the leading vehicle of a train such as, for example, the locomotive, is indicated at K . Mounted on this vehicle K is an inductor I disposed in a position for magnetic relationship with the wayside receiver IR when the vehicle K passes the location 1 . As will be fully described hereinafter, the inductor I is adaptable of being energized and a relatively strong magnetic field created thereby. Consequently, as the vehicle K enters the block Y the light beam is intercepted by the body of the vehicle to effect the release of the detecting relay IXR , and an electromotive force is induced in the wayside receiver IR by the inductor I to effect the energization of the receiving relay IZR . The wayside receiver IR is so positioned with respect to the light beam and the train-carried inductor I is so positioned with respect to the head end of the vehicle K , that the light beam is intercepted, relay IXR is released and its back contact 15 is closed just prior to the energizing of the relay IZR in response to the electro-motive force induced in the receiver IR . Hence, the detecting relay IXR is released and the receiving relay IZR is picked up and held energized by its stick circuit as the head end of a train enters the block Y , and they remain in such positions until the rear end of the train passes beyond the light beam. In other words, these two vehicle controlled actuators, one consisting of a photo-electric device and the other consisting of an electromagnetic device are so operated that when the front end of a train enters the block Y the detecting relay IXR is released and the receiving relay IZR is picked up sequentially and they are subsequently retained at these respective positions until the entire train passes into the block Y . The location 3 and all other signal locations of my system are provided with two actuators similar to these two actuators of location 1 .

Each block is equipped with a registration relay designated by the reference character S plus an exponent corresponding to the location, and a release relay designated by the reference character SP plus an exponent corresponding to the location, and these relays are effective to store the registration of a train into the block until the full sequence of operation is performed registering the train out of that particular block, and then to release such stored registration. Concurrently with the deenergizing of the detect-

ing relay 1XR and the energizing of the receiving relay 1ZR a pickup circuit is completed for the registration relay 1S of the block Y, from battery terminal B, front contact 22 of relay 1ZR, wire 23, back contact 24 of relay 1XR, wire 25, front contact 26 of a relay 1HS to be shortly referred to, wire 27, winding of relay 1S and to the C battery terminal, and the registration relay 1S is energized. Prior to the release of the detecting relay 1XR, the relay 1HS, the front contact 26 of which is interposed in the pickup circuit of the registration relay 1S, was energized in a manner to subsequently appear and a stick circuit had been completed to retain it energized. This stick circuit includes the following elements, battery terminal B, front contact 28 of relay 1XR, wire 29, back contact 30 of relay 1S, wires 31 and 32, front contact 33 of relay 1HS, wire 34, front contact 35 of a line control relay 1HD to be later described, wire 36, winding of relay 1HS and to the C battery terminal. This stick circuit was broken when relay 1XR was de-energized and hence the relay 1HS was also de-energized, however, relay 1HS did not immediately open its front contacts since it is slow releasing in character. Thus, the registration relay 1S is picked up as described above before the front contact 26 of the relay 1HS is opened.

With the registration relay 1S once picked up it is retained energized over a stick circuit consisting of two paths, a first one of which extends from the B battery terminal over the front contact 37 of relay 1HD, wire 38, front contact 39 of relay 1S, winding of that relay and thence to the C battery terminal. The second path of this stick circuit extends from the B battery terminal over the back contact 40 of a release relay 1SP, wires 41 and 38, and thence as before traced for the first path. It follows that the registration relay 1S once picked up in response to a train entering the block Y is released only when the relay 1HD is deenergized and its front contact 37 opened, and the release relay 1SP is picked up and its back contact 40 opened at the same time.

The release relay 1SP for the block Y is normally deenergized as shown and may be energized by virtue of a line circuit traced from the B battery terminal at location 3 over front contact 78 of the detecting relay 3XR, wire 79, front contact 80 of the registration relay 3S for the block Z, wire 125, normally closed contact 126 of a push button 3PB to be later referred to, line wire 81, winding of the relay 1SP and thence to the terminal C and back over the common line wire C1 to the terminal C of the battery at the location 3. It follows that the release relay 1SP is picked up only after the registration relay 3S for the block Z has been picked up and stuck energized in response to the head end of a train entering the block Z, and the detecting relay 3XR has been reenergized in response to the rear end of such train passing out of the block Y and into the block Z. As set forth above, the release relay 1SP when thus picked up opens at its back contact 40 one of the two parallel paths of the stick circuit for the associated registration relay 1S to release that relay. Hence, the relay 1SP functions to clear out the registration of a train into the block Y when a proper registration of the train into the next block Z and the registration of the rear end of the train out of the block Y are completed, it being understood, of course, that the line control relay 1HD functions to open the other path of the stick circuit for the relay 1S in a manner to be subsequently ex-

plained. The control of the registration and release relays of the remaining blocks of my system is similar to that explained for the relays 1S and 1SP of block Y.

A conventional polarized line control relay and an associated slow release repeater relay are used at each location to effect a control of a signaling device, and under certain conditions to effect a control of the registration relay. Furthermore, the polarized line control relay of one location is energized in series with a slow release stick relay at the location next in advance, the latter relay functioning under certain conditions to stick the line circuit open. The line control relay 1HD of location 1, for example, receives current from the B terminal of the battery at location 3 through the winding of a slow release stick relay 3XS, front contact 64 of that relay, wire 65, back contact 66 of the receiving relay 3ZR, front contact 67 of the detecting relay 3XR, wire 68, normally closed contact 69 of the push button 3PB, wire 70, front pole-changing contact 71 of a relay 3HS, line wire 72, winding of relay 1HD, line wire 73, a second front pole-changing contact 74 of relay 3HS and to the C terminal of the battery at location 3, and the relay 1HD is energized with current of a polarity which I will call normal polarity, the relay 3XS being also picked up. It is clear that with the relay 3HS released and its back pole-changing contacts 75 and 76 closed and the other elements of the circuit for the relay 1HD remaining as described, the relay 1HD is energized with current of the reverse polarity, the relay 3XS being retained picked up during such reversal of polarity since it is slow releasing in character. It is to be seen that in the case the line circuit for the relays 1HD and 3XS is opened and these relays are released, they can be reenergized only in the event a path is closed around the front contact 64 of relay 3XS. Such a shunt path is provided and includes a normally open front contact 77 of the registration relay 3S, as will be understood upon an inspection of Fig. 1b.

The repeater relay 1HS associated with the line control relay 1HD is provided with two pickup circuits in addition to the previously traced stick circuit by which it is normally retained energized. One such pickup circuit includes the battery terminal B, front contact 28 of the detecting relay 1XR, wire 29, back contact 30 of relay 1S, wires 31 and 94, front contact 95 of relay 1SP, wires 96 and 34, front contact 35 of relay 1HD, wire 36, winding of relay 1HS and thence to the C battery terminal. The other pickup circuit is the same as the one just traced up to the wire 94 and thence over wire 97, a normally open contact 98 of a push button 1PB, wire 99 to the wire 34 and thence as before traced for the first pickup circuit. The manner whereby the line control relay 1HD, the repeater relay 1HS and the stick relay 3XS function will appear as the specification progresses.

As here shown, each block is equipped with two train signaling devices one of which is a wayside signal designated by the reference character G with an exponent corresponding to its location, and the other of which is a wayside inductor designated by the reference character V with an exponent corresponding to the location and which inductor is the roadside portion of an intermittent train stop system to be described hereinafter. The wayside signals G may be of any of the well-known standard types now in general use and as here shown each is a color light signal adapt-

ed to display a clear, an approach and a stop indication. The clear signal lamp 49 for the signal 1G, for example, is illuminated by virtue of an operating circuit which includes the B battery terminal, back contact 42 of the registration relay 1S, wire 43, front contact 44 of relay 1HS, wire 45, front neutral contact 46 and left-hand polar contact 47 of relay 1HD, wire 48, lamp 49 and to the C battery terminal. The approach signal lamp 50 of signal 1G is illuminated by virtue of a circuit which is the same as just traced for the clear signal lamp 49 up to the front neutral contact 46 of relay 1HD and thence over the right-hand polar contact 51, wire 52, lamp 50 and to the C battery terminal. The operating circuit for the stop signal lamp 53 of signal 1G includes two paths the first of which extends from the B battery terminal over front contact 54 of relay 1S, wire 55, lamp 53 and to the C battery terminal. The second path for the lamp 53 includes the back contact 42 of relay 1S, wire 43, back contact 56 of relay 1HS and thence as before traced for the first path. All other wayside signals are provided with similar operating circuits.

The operating winding 57 of the wayside inductor 1V of the second signaling device at location 1 is normally short circuited by virtue of a circuit which may be traced from the right-hand terminal of the winding 57 over wire 58, front contact 59 and left-hand polar contact 60 of relay 1HD, wire 61, front contact 62 of relay 1HS and wire 63 to the left-hand terminal of the winding 57. It follows that the winding 57 of the wayside inductor 1V is short circuited under the condition that causes the signal 1G to display a clear indication, but that the winding 57 is open circuited under the conditions that cause the signal 1G to display either an approach or a stop indication. As will appear when the train-carried apparatus is described, the wayside inductor 1V has its winding 57 short circuited to permit a train-carried receiver R1 of the vehicle K to pass over it without causing an automatic application of the vehicle brakes, and has its winding 57 on open circuit for causing an automatic application of the train brakes when the train-carried receiver R1 passes over it. The wayside inductor 1V is preferably similar in construction to the wayside receiver 1R and is located slightly in the rear of the light beam of location 1. The inductor 1V is mounted parallel with the track and at a distance outside of the traffic rails slightly greater than the receiver 1R. Such spacing of the wayside receiver 1R and wayside inductor 1V permits the train-carried receiver R1 to pass by the wayside receiver 1R without magnetic influence, and the train-carried inductor 1 to pass by the wayside inductor 1V without magnetic influence.

To authorize a vehicle or train to move from the siding W to the main track and to provide the clearing out of the block registration when a train moves to the siding, the following equipment is provided at the switch 3W. As shown schematically by a dotted line, a switch circuit controller of the usual type is operatively connected with the switch 3W, the adjustment being such that the contacts 82, 83, and 84 of such circuit controller are set in the position indicated by the solid lines when the switch 3W is set for main line movements and are moved to the dotted line positions when the switch is set for movements in and out of the siding. A slow release relay 3WR and a manually oper-

ated push button 3WP are so arranged that at such time as the switch 3W is set for main line movements and the contact 84 is closed and the push button 3WP is depressed and its contact 85 is closed, a simple circuit easily traced is completed and the relay 3WR is energized. The relay 3WR when picked up closes at its front contact 86 a simple circuit for an indicating lamp 3PK, closes at its front contact 87 a circuit effective to energize the release relay 3SP, as will be readily understood by an inspection of Fig. 1b, and closes at its front contact 88 a circuit connection for shunting around the stick contact of the XS slow release stick relay at the next location east of the switch 3W. A switch indicator 3K is controlled over a line circuit which is carried back for a sufficient number of locations to give a desired approach indication and which line circuit includes the front contact 89 of the repeater relay 3HS, line wire 90, front contact 91 of the repeater relay 1HS and line wire 92, as will be understood by an inspection of the drawings, it being further understood that the line wire 92 is connected with a B terminal of a current source at some location to the left of the location 1.

The equipment of each signal location also includes a three-position manually operated push button indicated by the reference character PB with an exponent corresponding to the location and the function of which will appear when the operation of the system is described.

Referring now to Fig. 2, the train-carried equipment includes beside the inductor I and the receiver R1 shown mounted on the vehicle K of Fig. 1a, a control relay MS, an electropneumatic valve EP, two manually operated circuit controllers AT and AT1, a resistor M and a rectifier SA. The equipment will also include, of course, a suitable source of current and a housing for the apparatus. As here shown, the train-carried equipment is that for a well-known intermittent train stop system in present day use with the inductor I and the circuit controller AT1 added. This apparatus will be described only insofar as seems necessary for an understanding of the operation of my invention in conjunction with such train stop systems since the specific structure of such train-carried equipment forms no part of my invention and it will be understood that other forms of train stop apparatus may be used if found desirable to do so. With the train-carried apparatus in its normal position, that is, the position illustrated in Fig. 2, the principal or hold clear circuit may be traced from the positive terminal B of the train-carried current source over wire 100, contact 101, an armature 103 and a second contact 102 of the relay MS, winding of that relay, secondary winding 104 of the receiver R1, a portion of the primary winding 105 of that receiver, winding of the magnet of the valve EP and thence over wire 106 to the negative terminal C of the current source. The primary winding 105 of the receiver R1 is also energized through a branch circuit extending from the B battery terminal up to the armature 103 of relay MS, thence over a normally closed contact 107 of the manually operated circuit controller AT1, the full portion of the primary winding 105, winding of magnet valve EP and wire 106 to the C terminal of the current source. This latter branch circuit is thus in parallel with the first circuit which includes the winding of the relay MS, and the combined influences of the two currents flowing in the winding of the magnet valve EP is ef-

fective to energize that magnet and hold the train brakes released, whereas operation of the relay armature 103 out of engagement with the contacts 101 and 102 to open both circuits, or the raising of the circuit controller AT1 to open the contact 107 and thereby stop the flow of current of one of the circuits, is effective to release magnet valve EP and cause an application of the train brakes. It will be understood, of course, that in accordance with usual practice a delayed action of the valve EP is provided whereby the magnet of the valve may be deenergized for a period of, say, four seconds before an application of the train brakes is effected. The relay MS is of the type including a permanent magnet and a biasing element (not shown) whereby the armature 103 is snapped to the right from the position shown in Fig. 2 to a position out of engagement with the contacts 101 and 102 when the winding of the relay is deenergized. The arrangement is such that when the receiver RI passes over a wayside inductor such as the inductor 1V, and the winding of the wayside inductor is short circuited, as would be the case at the entrance of a clear block, the counter-electromotive force generated in the secondary winding 104 is so slight that the relay MS does not open and the vehicle may proceed without interruption. If, however, the winding of the wayside inductor is on open circuit, as would be the case at the entrance of a block where the wayside signal indicates stop or approach, the counter-electromotive force generated in the secondary winding 104 is opposite in polarity to the energy supplied by the train-carried current source, and is sufficient to cause the relay MS to be operated and open its own circuit as well as the circuits to the magnet valve EV with the result that a brake application is effected. The circuit for picking up or restoring the relay MS to its normal position includes a normally open contact 108 of the circuit controller AT, the circuit being as follows, terminal B, contact 108, winding of relay MS, secondary winding 104, a portion of the primary winding 105, winding of magnet valve EP and to the C terminal of the current source. With the circuit controlled AT actuated to close the contact 108 for the picking up of the relay MS a second contact 109 is also closed to complete an energizing circuit for the primary winding 105 and which circuit includes the resistor M and the full portion of the primary winding 105 as will be understood by an inspection of Fig. 2. It is to be noted that the circuits completed by the operation of the controller AT are the usual forestalling circuits provided with the usual automatic train stop systems.

The rectifier SA is connected with a shunt path across the relay contacts, windings of the receiver RI, and winding of magnet valve EP. This rectifier SA is so positioned as to offer a high resistance to the flow of current supplied by the vehicle source but serves as a by-pass for the inductive effect created in the windings of the vehicle apparatus, and hence it serves as a spark arrester when the relay contacts are operated.

Operation of the circuit controller AT1 from engagement with the contact 107 into engagement with the contact 110 is effective to energize the winding 111 of the train-carried inductor I, the circuit being easily traced and including the contact 101-103 of the relay MS. As here shown, the contact 107 of the controller AT1 assures that the controller AT1 is not permanently raised and the inductor I unnecessarily energized, since

with the contact 107 open the electropneumatic valve EP is released. However, it is to be pointed out that the inductor I may be continuously energized if desired. In this latter case, the electropneumatic valve EP would be controlled over 5 the usual circuit with the contact 107 omitted.

In describing the operation of the apparatus, I will first describe a train moving east straight through the blocks X, Y and Z. Next, I will describe a train moving east into the block Z and 10 backing into the siding W and clearing the main line, and then I will describe a train entering the block Z from the siding W. Lastly, I will describe a movement representing a train backing into a block against the current of traffic, and the manual "keying by" operation for at times clearing the signaling devices to authorize a train to move into the block in advance.

Referring to Figs. 1a and 1b and assuming that the signal 1G displays a clear indication and the vehicle K shown at the left-hand end of Fig. 1a advances toward the east, the front end of such vehicle first intercepts the light beam at location 1 and the detecting relay 1XR is released. At this point, the operator of the vehicle operates the controller AT1 to energize the train-carried inductor I with the result that as the inductor I passes over the wayside receiver RI, an electromotive force is induced in the receiver and the receiving relay 1ZR is picked up. Concurrently, with the operation of the relays 1XR and 1ZR the registration relay 1S is picked up and stuck energized thus storing the registration of the vehicle into the block Y. The picking up of the registration relay 1S is effective to 30 extinguish the clear signal lamp 49 of signal 1G and to illuminate the stop signal lamp 53, and also to release the repeater relay 1HS. Just prior to the registration of the vehicle into the block Y the winding 57 of the wayside inductor 40 1V was short circuited, and hence as the train-carried receiver RI passed over that inductor the train-carried relay MS was not released and the automatic train stop apparatus was unaffected as the vehicle entered the block Y. The vehicle K advances east through the block Y under the clear signal indication received at location 1, and as the vehicle passes location 3 and enters the block Z the entering of the vehicle into the block Z is registered by virtue of the registration relay 3S 50 being picked up and stuck energized in the same manner as explained for the registration relay 1S, with the result that the signal 3G is set at stop and relay 3HS is released to open circuit the winding of inductor 3V. With the releasing of 55 the detecting relay 3XR at location 3 and the opening of its front contact 67, the line circuit for the relay 1HD is opened and that relay as well as its associated stick relay 3XS are deenergized. The releasing of the relay 1HD and the opening of 60 its front contact 37 opens one path of the stick circuit for the registration relay 1S but that relay is still retained energized over the second path of its stick circuit which includes the back contact 46 of the release relay 1SP since the release 65 relay 1SP remains deenergized due to the fact that the front contact 78 of the relay 3XR is now open.

When the rear of the train of which the vehicle K is the leading vehicle passes beyond the location 1, whether that is before or after the head end of the train passes the location 3, the relay 1XR is reenergized and the relay 1ZR is released since its stick circuit is now open at the back contact 15 of relay 1XR. The registration relay 75

1S remains energized, however, as the rear end of the train vacates the block X since the release relay 1SP is still down and its back contact 40 closed. The line circuit for the relay 1XS at location 1 and is associated HD line control relay at the location next to the left of location 1 is now, however, supplied with current, this circuit including battery terminal B, winding of the relay 1XS, front contact 112 of relay 1S, back contact 113 of relay 1ZR, front contact 114 of relay 1XR, contact 130 of 1PB, back contacts 117 and 118 of relay 1HS and line wires 115 and 116. The polarity of the current supplied to this HD relay in the rear over the line wires 115 and 116 is of reverse polarity since the repeater relay 1HS is now down and its back pole-changing contacts 117 and 118 are closed. When the train advances east and the rear end of the train passes beyond the location 3, the relay 3XR is reenergized and the relay 3ZR is released. Since the front contact 80 of the registration relay 3S is now closed, the closing of the front contact 78 of the relay 3XR completes the line circuit for the release relay 1SP and that relay is picked up to open at its back contact 40 the second path of the stick circuit for the registration relay 1S and thus registration relay 1S is released to clear out the registration at location 1. It is to be noted that the release of the relay 3ZR is retarded 30 due to the snubbing action of the rectifier 3RX which is connected across its operating winding and thus shunting the current induced by the collapse of the flux in its magnetic structure. This retardation of the release of relay 3ZR is 35 of sufficient duration to hold the circuit for the line control relay 1HD open at back contact 66 long enough after the relay 3XR is reenergized to permit the energization of the release relay 1SP and the subsequent deenergization of the registration relay 1S, which is a quick release relay, before the relay 1HD is picked up and closes at its front contact 31 the first path of the stick circuit for the relay 1S. With the release relay 1SP picked up and its front contact 95 closed 40 and the relay 1S released and its back contact 30 closed, the energizing of the relay 1HD to close its front contact 35 completes the pickup circuit for the repeater relay 1HS since the relay 1XR is now energized and its front contact 28 is closed. 45 With the picking up of the relay 1HS and the closing of its front contact 44 the operating circuit for the lamp 50 is completed and signal 1G displays an approach indication since the relay 1HD is now energized by current of reverse polarity 50 and its right-hand polar contact 51 is closed. It is to be seen, therefore, that the clearing out of the registration at location 1 and the displaying of an approach indication by the signal 1G takes place only after the train has been registered 55 into the block Z, the signal 3G set at stop, the inductor 3V open circuited, and the rear end of the train has been registered out of the block Y by restoring relays 3XR and 3ZR to their normal position. When the train has advanced east out 60 of the block Z and the repeater relay 3HS has been reenergized in a manner similar to that explained for reenergizing the repeater relay 1HS, the current supplied to the relay 1HD at location 1 is then of normal polarity and the indication 65 of the signal 1G is changed from approach to a clear indication.

I will now assume that the vehicle K starts from its position in Fig. 1a and advances east and is registered into the block Z in the manner explained above, and has stopped at the switch 3W

preparing to back into the siding W. Under this condition, relay 3S is energized, relay 3HS is de-energized, relay 3HD is energized, assuming, of course, that the front end of the vehicle K has not advanced east of the next location to the right of location 3, and the release relay 3SP is deenergized. Also, the relays 3XS, 3ZR and 3XR at location 3 are now in the position shown. When the switch 3W is thrown to its reverse position to permit the train to back into the siding W, the circuit for the relay 3HD is opened at the contacts 82 and 83 and that relay is released and by virtue of its associated XS stick relay at the next location to the east the line circuit for the relay 3HD is stuck open. As previously pointed out, in order to register a train out of a block the HD relay must be deenergized and the SP release relay energized to release the S registration relay; and then the HD relay must be re-energized while the SP relay is still energized to permit the HS repeater relay to become energized and clear the wayside signal. Since the train at switch 3W did not register out of the exit end of the block Z, the release relay 3SP is deenergized and therefore the apparatus at the switch location must be effective to energize that relay as well as to deenergize and then reenergize line relay 3HD in order to register the train out of the block. This is accomplished by having a trainman depress the push button 3WP (which is placed under lock or may be in the form of a switch key circuit controller). The depressing of the push button 3WP after the switch 3W has been restored to its normal position causes the relay 3WR to be picked up and, since it is slow releasing in character, it does not open its front contact for several seconds after the push button 3WP is restored to its normal position. It is to be noted that the line control circuit for the relay 3HD is carried over the normally closed contacts 119 and 120 of the push button 3WP to check that the push button is restored to its normal position before the signal 3G can clear. Concurrently, with the energization of the relay 3WR and the closing of its front contact 81, current is fed to the release relay 3SP and that relay is picked up. Since the relay 3HD is now de-energized both paths of the stick circuit for the registration relay 3S are open and that relay is released, and the registration stored at the location 3 is cleared out. While the relay 3WR is energized and its front contact 88 is closed a path is completed around the stick contact of the XS relay at the next location to the right permitting thereby that relay and the relay 3HD to become reenergized. When the relay 3HD is thus reenergized and its front contact 123 is closed, the repeater relay 3HS becomes energized since the release relay 3SP is now picked up and its front contact 121 is closed, this circuit also including contact 78 of relay 3XR and back contact 129 of relay 3S. At the end of the slow release period of the relay 3WR that relay is released and hence the release relay 3SP is again deenergized. Consequently, the apparatus for block Z is restored to its normal position by the manipulation of the push button 3WP following the closing of the switch 3W. It is to be noted that with the energization of the relay 3WR and the closing of its front contact 86 the indicator lamp 3PK is lighted to indicate to the trainman that the relay 3WR is picked up.

I will now describe how a vehicle or train is registered into the block Z from the siding W. When the switch 3W is operated to its reverse

positon, the relay 3HD is deenergized due to its line circuit being opened at the contacts 82 and 83 and the relay 3HD is stuck deenergized by the action of the XS stick relay at the next location in advance. Concurrently, current is fed over the contact 84 of the switch circuit controller, wire 122, front contact 123 of relay 3HS, winding of registration relay 3S and to the C battery terminal and the registration relay 3S is picked up and is stuck energized over the path of its stick circuit which includes the back contact 124 of the release relay 3SP. The signal 3G is set to display a stop indication in response to the energizing of the registration relay 3S and, consequently, registration of the vehicle into block Z is accomplished by the operation of the switch only. Authorization to open the switch is obtained by the switch indicator 3K, the control of which, as stated hereinbefore, is carried to the rear for a sufficient number of signal locations to give a desired approach indication.

A move against the current of traffic into the block previously vacated cannot with safety be made except under flag protection, so I have provided for such operation when movement against the current of traffic is contemplated. Assuming the vehicle K is registered into the block Z and out of the block Y in the manner previously described, the signal 1G is permitted to display an approach indication authorizing a following vehicle to advance east past the location 1. Therefore, if the vehicle K in block Z is to be permitted to again enter the block Y from the right, a flagman is sent out to protect the movement. At the location 3 the flagman sets the push button 3PB at its center position where all contacts operated thereby are open. Since the line circuit for the relay 1HD includes the contact 69 of the push button 3PB that relay is deenergized and in turn its repeater relay 1HS is released and the signal 1G is set to indicate stop, the operating circuit for the stop lamp 53 of the signal 1G being closed at the back contact 42 of relay 1S and the back contact 56 of relay 1HS. Since a following train may actually have entered the block Y registering into that block while relay 1SP is energized, it is not desirable to permit relay 1S to become deenergized in response to the flagman operating the push button 3PB and releasing both relays 1SP and 1HD, therefore, relay 1SP must be released before the relay 1HD is released. This is accomplished by the contact 69 of the push button 3PB being adjusted to break its contact an instant after the contact 125 is opened. With the push button 3PB thus operated the vehicle in the block Z may back into the block Y under protection of the flagman, the open contact 126 preventing a false registration out of the block Y in the event a registration is stored at the location 1. When the vehicle which has backed into the block Y in the manner just explained, is ready to advance east again out of the block Y, the push button 3PB must be placed back at its normal position.

To "key-by" a stop signal when a train comes up to such stop signal, say the signal 1G for example, the trainman may depress the push button 1PB to its full down position and close the contact 98. If the block Y is not occupied by another train and the registration relay 1S is deenergized, the repeater relay 1HS is supplied with current over its pick-up circuit including the contact 98 and that relay is picked up to permit the clearing of the signal 1G. Should the signal fail to clear due to the relay 1HD being open for

whatever cause, the train must wait for a proceed indication or advance under proper orders and with proper flag protection.

Although I have herein shown and described only one form of apparatus embodying my invention, it is understood that various changes and modifications may be made therein within the scope of the appended claims without departing from the spirit and scope of my invention.

Having thus described my invention, what I claim is:

1. A signaling system comprising in combination with a trackway and a vehicle adapted to travel on the trackway, a plurality of electro-responsive registration means one at each of a plurality of spaced locations along the trackway and each normally deenergized, circuit means at each location for energizing the registration means and normally ineffective, vehicle actuated means at each location operative to render said circuit means effective only during the interval a vehicle passes the location, storage means at each location effective to retain the registration means energized, release means at each location controlled by the vehicle actuated means at the location next in advance and operative to deenergize the associated registration means in response to the vehicle passing such location next in advance, and vehicle signaling means controlled by the registration means.

2. A signaling system comprising in combination with a trackway and a vehicle adapted to travel on the trackway, a plurality of electro-responsive registration means one at each of a plurality of spaced locations along the trackway, an intermittent control means at each location for energizing the registration means and including a vehicle controlled actuator operative to render such control means effective when and only when a vehicle is passing the location, storage means at each location effective to retain the registration means energized, release means at each location controlled by the vehicle controlled actuator at a location in advance and operative to deenergize the associated registration means in response to the vehicle passing such location in advance, and vehicle signaling means controlled by the registration means.

3. A signaling system comprising in combination with a trackway and a vehicle adapted to travel on the trackway, a plurality of electro-responsive registration means one at each of a plurality of spaced locations along the trackway, an intermittent control means at each location for energizing the registration means and including a vehicle controlled actuator operative to render such control means effective when the front end of a vehicle passes the location and subsequently retains it effective until the rear end of the vehicle passes beyond the location, storage means at each location effective to retain the registration means energized, release means at each location controlled by the vehicle controlled actuator at a location in advance and operative to deenergize the associated registration means when and only when the entire vehicle has passed such location in advance, and vehicle signaling means controlled by the registration means.

4. A signaling system comprising in combination with a trackway and a vehicle adapted to travel on the trackway, a plurality of electro-responsive registration means one at each of a plurality of spaced locations along the trackway, a vehicle controlled actuator at each location op-

erated to one position when the front end of the leading vehicle of a train of several vehicles passes the location and subsequently operated to a second position when the last vehicle of said 5 train passes beyond the locations, a pickup circuit at each location for energizing the registration means and including a contact closed in said one position of the actuator, a stick circuit at each location effective to retain the registration 10 means energized, a release circuit for each location to deenergize the registration means and including a contact of the actuator at the location in advance and closed when such actuator in advance is operated to said second position, and 15 vehicle signaling means controlled by each registration means.

5. A signaling system comprising in combination with a trackway and a vehicle adapted to travel on the trackway, a plurality of electro-responsive registration means one at each of a plurality of spaced locations along the trackway, an intermittent control means at each location for energizing the registration means and including a light sensitive element operative to render 25 the control means effective to energize the registration means when the front end of the leading vehicle of a train of several vehicles passes the location and subsequently retains it effective until the rear end of the last vehicle of the train 30 passes beyond the location, storage means at each location effective to retain the registration means energized, release means at each location controlled by the light sensitive element at a location in advance and operative to deenergize the 35 associated registration means when and only when the last vehicle of the train has passed such location in advance, and vehicle signaling means controlled by the registration means.

6. A signaling system comprising in combination 40 with a trackway and a vehicle adapted to travel on the trackway, a plurality of electro-responsive registration means one at each of a plurality of spaced locations along the trackway, a vehicle actuated means at each location having a normal position and adapted to be moved to an operated position when and only when some portion of a vehicle occupies the location, means governed by the vehicle actuated means in the operated position for energizing the associated 45 registration means, storage means at each location effective to retain the registration means energized, release means at each location controlled jointly by the vehicle actuated means and the registration means at a location in advance 50 and operative to deenergize the associated registration means in response to the registration means in advance energized and the vehicle actuated means in its normal position, and signaling means controlled by each registration means.

60 7. A signaling system comprising in combination with a trackway and a vehicle adapted to travel on the trackway, a plurality of registration relays one at each of a plurality of spaced locations along the trackway, a vehicle actuated means at each location having a normal position and adapted to be moved to an operated position when and only when some portion of a vehicle occupies the location, a pickup circuit for each registration relay and including a contact closed 65 only in the operated position of the associated vehicle actuated means, a release relay at each location and normally deenergized, a stick circuit for each registration relay and including a back contact of the associated release relay, a line 70 circuit for energizing each release relay and in-

cluding a front contact of the registration relay at a location in advance and a contact closed only in the normal position of the vehicle actuated means at such location in advance, a signaling device at each location, and operating circuits 5 for each signaling device selectively controlled by the associated registration relay.

8. A signaling system comprising in combination with a trackway and a vehicle adapted to travel on the trackway, a plurality of registration 10 relays one at each of a plurality of spaced locations along the trackway, a vehicle actuated means at each location having a normal position and adapted to be moved to an operated position when and only when some portion of a vehicle 15 occupies the location, a pick-up circuit for each registration relay and including a contact closed only in the operated position of the associated vehicle actuated means, two stick circuits for each registration relay each effective to 20 retain the registration relay energized, a first release means controlled by the vehicle actuated means at the location next in advance effective to open one of the stick circuits when said actuated means at the point in advance is moved to 25 its operated position, a second release means controlled jointly by the registration relay and the vehicle actuated means at the location next in advance and effective to open the other stick circuit when said registration relay is energized and 30 the vehicle actuated means is restored to its normal position, and signaling means controlled by each registration relay.

9. A signaling system comprising in combination with a trackway and a vehicle adapted to 35 travel on the trackway, signaling means one at each of a plurality of spaced locations along the trackway, a registration relay at each location effective when energized to set the signaling means at the same location at stop but normally 40 deenergized, a vehicle actuated means at each location having a normal position and adapted to be moved to an operated position when the front end of a vehicle passes the location and subsequently held in that position until the rear end 45 of the train passes beyond the location, control means governed by the vehicle actuated means when operated for energizing the registration relay, a stick circuit at each location effective to retain the registration relay energized, and release means at each location controlled jointly by the registration relay and the vehicle actuated means at the location next in advance and effective to open said stick circuit when and only 50 when the vehicle actuated means at the location in advance is operated and the registration relay at that location is energized and the vehicle actuated means is subsequently returned to its normal position.

10. A signaling system comprising in combination with a trackway and a vehicle adapted to travel on the trackway, signaling devices one located at each of a plurality of spaced locations along the trackway, photo-electric means at each location including a light sensitive element responsive to any portion of a vehicle occupying the location, electro-magnetic means at each location including a trackway magnetic receiver responsive to the influence of a vehicle-carried inductor as a vehicle passes the location, and 65 means controlled jointly by the light sensitive element and the magnetic receiver of each location for governing the signaling device.

11. A signaling system comprising in combination with a trackway and a vehicle adapted to 70

travel on the trackway, signaling devices one located at each of a plurality of spaced locations along the trackway, a first contact at each location, means at each location for operating said 5 first contact when the front end of a vehicle passes the location and for subsequently maintaining said contact in its operated position until the rear end of the vehicle passes beyond the location, a second contact at each location, trackway 10 means at each location responsive to the influence of a vehicle-carried means effective to operate said second contact when the vehicle-carried means passes the trackway means of the same location, and means controlled jointly by the two 15 contacts of a location when operated for governing the signaling device of the same location.

12. A signaling system comprising in combination with a trackway and a vehicle adapted to travel on the trackway, signaling devices one 20 located at each of a plurality of spaced locations along the trackway, a first electroresponsive means at each location including a light beam transverse to the trackway and a contact operated when the front end of the leading vehicle of a 25 train of several vehicles intercepts the light beam and subsequently remains operated until the rear end of the last vehicle of such train passes beyond the light beam, a second electroresponsive means at each location including a trackway 30 magnetic receiver responsive to the influence of a vehicle-carried inductor and a contact operated when a vehicle-carried inductor passes over the trackway receiver, and means at each location controlled jointly by said two contacts of the 35 same location and effective to operate the signaling device of the same location and the signaling device at a location in the rear in response to said operation of the contacts.

13. A signaling system comprising in combination with a trackway and a vehicle adapted to travel on the trackway, a first electroresponsive means including a light beam transverse to the trackway and a contact operated when the front end of the leading vehicle of a train of several 45 vehicles intercepts the light beam and subsequently remains operated until the rear end of the last vehicle of such train passes beyond the light beam, a second electroresponsive means including a trackway magnetic receiver responsive to the influence of a vehicle-carried inductor and a contact operated when such vehicle-carried inductor passes over the trackway receiver, and a signaling device controlled jointly by said two contacts.

55 14. A signaling system comprising in combination with a trackway and a vehicle adapted to travel on the trackway, a first electroresponsive means including a light beam transverse to the trackway and a contact operated when the front 60 end of the leading vehicle of a train of several vehicles intercepts the light beam and subsequently remains operated until the rear end of the last vehicle of such train passes beyond the light beam, a second electroresponsive means including a trackway magnetic receiver responsive to the influence of a vehicle-carried inductor and a contact operated when such vehicle-carried inductor passes over the trackway receiver, and a signaling device controlled jointly by said two 65 contacts and operated when and only when both contacts are operated at the same time.

70 15. A signaling system comprising in combination with a trackway and a vehicle adapted to travel on the trackway, photo-electric means including a light beam disposed along the track-

way for interception by a vehicle passing along the trackway and a contact operated when the front end of a vehicle intercepts the light beam and subsequently remains operated until the rear end of the vehicle passes beyond the light beam, 5 electromagnetic means including a receiver disposed along the trackway for inductively receiving an electromotive force from a vehicle-carried inductor and a contact operated by such electromotive force in response to a vehicle passing the 10 receiver, and a signaling device controlled jointly by said two contacts.

16. A signaling system comprising in combination with a trackway and a vehicle adapted to travel on the trackway, photo-electric means including a light beam disposed along the trackway for interception by a vehicle passing along the trackway, electromagnetic means including a receiver disposed along the trackway for inductively receiving an electromotive force from a 20 vehicle-carried inductor, and a vehicle signaling device controlled jointly by said photo-electric means and said electromagnetic means.

17. A signaling system comprising in combination with a trackway and a vehicle adapted to travel on the trackway, photo-electric means including a light beam disposed along the trackway and a detecting relay operated to a given position when the front end of a vehicle intercepts the light beam, electromagnetic means including a receiver disposed along the trackway for inductively receiving an electromotive force for a vehicle-carried inductor and a receiving relay energized by such electromotive force in response to a vehicle passing the receiver, and a 35 signaling circuit including in series a contact of the detecting relay closed in said given position and a front contact of the receiving relay.

18. A railway signaling system comprising a stretch of railway track, a plurality of signaling 40 devices one located at each of a plurality of spaced locations along the track, a traffic responsive device at each location, a line relay and a stick relay at each location; a line circuit controlled by each traffic responsive device and including the winding of the stick relay at the location of said device, a front contact of such stick relay and the winding of the line relay for the location next in the rear in series whereby said line circuit once opened is stuck open; means 50 controlled by the traffic responsive device for at times closing a shunt path around the stick contact, and means controlled by each line relay for governing the signaling device at the same location.

55 19. A railway signaling system comprising, a stretch of railway track including a track switch, a signal located adjacent the entrance of said stretch for governing traffic therethrough, a registration relay effective when energized to set 60 the signal at stop but normally deenergized, train actuated means disposed adjacent the entrance of the stretch operative to energize said registration relay in response to a train entering the stretch, a stick circuit effective to subsequently 65 retain said relay energized, a first controller operatively connected with said switch, a manually operable circuit controller located adjacent the switch, and means controlled jointly by said two circuit controllers for at times opening said stick 70 circuit to release said relay.

75 20. A railway signaling system comprising a stretch of railway track including a track switch, a signal located adjacent the entrance of said stretch for governing traffic therethrough, a 75

registration relay effective when energized to set the signal at stop but normally deenergized, train actuated means disposed adjacent the entrance of the stretch and actuated to a given position in response to a train entering the stretch, a circuit controller operatively connected with said switch, a first pickup circuit for said relay including a

contact of said train actuated means and closed in said given position, a second pickup circuit for said relay including a contact of said circuit controller and closed when said track switch is open, and a stick circuit effective to subsequently retain said relay energized. 5

RALPH R. KEMMERER.
